UNITED STATES PATENT OFFICE.

ARTHUR BURGESS, OF PHILADELPHIA, PENNSYLVANIA, ASSIGNOR TO
JOSEPH H. BROMLEY, OF PHILADELPHIA, PENNSYLVANIA.

DESIGN FOR A LACE CURTAIN.

SPECIFICATION forming part of Design No. 36,020, dated August 19, 1902.
Application filed June 26, 1902. Serial No. 113,174. Term of patent 7 years.

To all whom it may concern:

Be it known that I, ARTHUR BURGESS, a subject of the King of Great Britain, residing at Philadelphia, in the State of Pennsylvania, 5 have invented and produced a certain new, original, and ornamental Design for Lace Curtains, of which the following is a full, clear, and exact description, reference being had to the accompanying drawing, forming a part 10 of this specification.

My invention relates to the surface ornamentation of lace-curtain fabrics in which the ornamental pattern or design is produced in the weaving; and it consists in the ornamental design for a lace curtain as illustrated 15 in the drawing, in which is represented a curtain-body A, having upon and extending along the edges of two of its sides the design for a lace-curtain body constituting my invention, the characteristic and distinguishing 20 features of which are as follows: Within an edge border (represented in the drawing by the edge a u) is a series of large scroll figures b. These are arranged with their short curved

ends b' alternating with each other on opposite sides in the concrete design and with their contacting edges so close together as to give the effect of a single long connected scroll figure, including the larger corner scroll b², which has an appendant small scroll b³. 25 These scroll figures b b² b³ are in turn each made up of a series of small leaves c, giving the whole the appearance of a scroll-wreath. In the curvilinear spaces on the ground fabric formed by the scrolls there is instead of 30 the solid or plain surface, like the body of the curtain-body, a small lace-like design d, the scrollwork surrounding and inclosing it.

I claim as new and of my invention--
The ornamental design for a lace curtain 35 substantially as shown and described.

In testimony whereof I have hereunto affixed my signature this 31st day of May, A. D. 1902.

ARTHUR BURGESS.
